UNITED STATES PATENT OFFICE

FRED W. TOBEY, OF GRAND RAPIDS, MICHIGAN

CARD-TRAY CABINET

Application filed August 19, 1927. Serial No. 214,091.

The objects of this invention are,

First, to provide a simple construction of card tray cabinet whereby simple trays can be made use of and withdrawn from the cabinet to their limits and made completely removable and accessible.

Second, to provide an improved drawer slide for supporting card trays in a cabinet.

Third, to provide improved drawer slide 10 and card tray combination for a cabinet.

Objects pertaining to details of construction will appear from the detailed description to follow. The invention is defined in the claims. A structure which is a preferred embodiment of the invention is illustrated in the accompanying drawing, in which:

Fig. 1 is a perspective view of a complete card cabinet with its drawer slides and card trays made in accordance with my invention.

20 Fig. 2 is a detail view showing one of the slides withdrawn to its limit, showing one of a pair of card trays in place.

Fig. 3 is one of the card trays removed.

Fig. 4 is a detail sectional view on plane 25 4—4 of Fig. 1, showing the arrangement of the card trays on the drawer slide and boards.

Fig. 5 is a detail perspective view showing the under side of one of the card trays and its engaging cross cleat.

30 Fig. 6 is an enlarged vertical detail sectional view on line 6—6 of Fig. 4, showing the relation of the lock spring to the card tray and its cross cleat.

The parts of the drawing will be identified 35 by numerals of reference which are the same in all the views.

1 is the card cabinet, supported on the usual base 2 and provided with the usual top 3. 4 is a drawer slide board designed and adapted 40 to support card trays placed thereon. 5, 5 are a plurality of simple card trays which are disposed and rest upon the drawer slide board, having handles 52 at both ends. The drawer slide board 4 is supported on roller 45 bearing drawer extension slides 41 so that

the drawer slide 4 can be completely withdrawn from the cabinet and be supported by the drawer extensions, these drawer extensions being of a usual design in common use.

The drawer slide 4 is provided with side 50 rails 42 to embrace the sides of the card trays 5. A spring stop 43 is disposed at the front of the drawer slide board to engage cross bar 51 or other stop on the under side of the card tray 5, and retain the card tray in the cabinet 55 when the cabinet is locked. This spring stop 43 is horizontally disposed and permits the tray 5 to slide to place when the drawer slide boards 4 are closed and automatically to lock 60 in place.

I have described my invention in its preferred form. It very clearly could be varied in many particulars. The detail of the extension for the drawer slide boards could be modified indefinitely, such extensions being 65 common and need not particularly be provided with roller bearings, although that is desirable.

Having thus described my invention, what I claim as new and desire to secure by Letters 70 Patent is:

1. In a card cabinet structure, the combination of a cabinet with drawer slide board with ways for card trays having drawer suspension extensions for permitting the complete 75 withdrawal and suspension of the said drawer slide board, a plurality of card trays dimensioned and adapted to rest in the ways on said drawer slide board and with fronts coinciding with the front thereof and with cross 80 cleats underneath, and depressible detent spring stops on said slide board for engaging said cross cleats underneath the card trays and retaining them in position when the cabinet is closed and locked, and permitting the 85 lifting and removal of said trays when the drawer slide board is pulled out.

2. In a card cabinet structure, the combination of a cabinet with drawer slide board with ways for card trays, a plurality of card trays 90

dimensioned and adapted to rest in the ways on said drawer slide board and with fronts coinciding with the front thereof and with cross cleats underneath, and depressible detent spring stops on said slide board for engaging said cross cleats underneath the card trays and retaining them in position when the cabinet is closed and locked, and permitting the lifting and removal of said trays when the drawer slide is pulled out.

10 In witness whereof I have hereunto set my hand.

FRED W. TOBEY.
